UNITED STATES PATENT OFFICE.

FRIEDRICH ALBIN SCHANZ, OF DRESDEN, GERMANY.

APPARATUS FOR DEMONSTRATING OCULAR FLUORESCENCE.

1,105,310.

Specification of Letters Patent.

Patented July 28, 1914.

Application filed September 22, 1913. Serial No. 791,059.

To all whom it may concern:

Be it known that I, FRIEDRICH ALBIN SCHANZ, a resident of the city of Dresden, in the Empire of Germany, and a subject 5 of the King of Saxony, have invented certain new and useful Improvements in or Relating to Apparatus for Demonstrating Ocular Fluorescence, of which the following is a specification.

10 It has been proved that the known fluorescence of the human eye is produced by daylight.

The present application relates to an apparatus by means of which it is possible to observe the fluorescence of one's own eye.

The apparatus is chiefly intended for teaching purposes, that is to say, forms a medium for teaching.

A construction of the apparatus is shown 20 in the accompanying drawing in which—

Figure 1 is a vertical longitudinal section, and Fig. 2 a horizontal cross section.

It chiefly consists of a box forming a dark chamber, the inner walls of which are 25 kept black. Inside one wall *a* of the said box is arranged a mirror *b*. On the opposite side, the box is opened, and the upper and bottom walls *c* and *d* are provided with such recesses *e* and *f* that, on the box being 30 brought against the face of the user in the manner shown in Fig. 1, as perfect closing as regards light is obtained as possible. In order to improve this action, the edges of the recesses are provided with plush strips *g* 35 which enable a tight closing to be obtained.

The lateral walls *h* and *i* are provided with openings. For closing the said openings, is used a plate *k* of dark blue glass and a wooden slide *l*. In order to enable 40 these two plates to be easily interchanged with each other, guides are formed in the lateral walls *h* and *i* by means of ledges *m* and the two plates *n*. After the introduction, the plates are held fast by the fastener 45 *o*. On the lower side of the box is provided a plate *p* with a screw threaded perforation *q* in order to enable the box to be secured if desired to a stand or the like. The apparatus is used by bringing the box,

in the manner shown in Fig. 1, close to the 50 face of the user. Daylight passes through the dark blue glass plate *k*, chiefly into the eye of the user which is on the glass plate side. The user looks into the mirror *b* and sees there the image of the eye in which the 55 pupil, owing to the action of rays of light of short wave-length, is fluorescent, and therefore appears gray. The observation requires strong daylight, preferably sun-light.

I claim:

1. An apparatus for demonstrating ocular fluorescence, consisting of a box forming a dark chamber and provided on one side with an opening adapted to the shape of the face, 65 and on the opposite side with a mirror arranged in the box, while in one of the other wall surfaces is inserted a dark blue glass plate or the like, through which daylight falls on the eyes of the user holding the apparatus in front of his face.

2. An apparatus for demonstrating ocular fluorescence, comprising a box forming a dark chamber and provided at one side with recessed edges adapted to the shape of the 75 face, and on the opposite side with a mirror arranged in the box, while in one of the other wall surfaces is inserted a dark blue glass plate or the like, through which daylight falls on the eyes of the user holding 80 the apparatus in front of his face, and a covering of suitable yielding material over said recessed edges for closing the same against ingress of light when using the apparatus.

3. An apparatus for demonstrating ocular fluorescence, comprising a box forming a dark chamber and provided at one side with an opening adapted to the shape of the face, and at the opposite side with a mirror arranged in the box, the two lateral walls of the box being provided with openings, a dark blue glass plate secured detachably in place over the opening in one lateral wall, and a plate impervious to light secured 90 detachably in place over the opening in the other lateral wall.

4. An apparatus for observing the fluo-

rescence of the human eye, comprising a dark chamber, a mirror therein, an opening for the eyes opposite the mirror, and means for admitting dark blue colored light to the chamber laterally of the line of vision between the eyes and the mirror.

Dated this 4th day of September 1913.

In testimony that I claim the foregoing as my invention, I have signed my name in presence of two subscribing witnesses.

FRIEDRICH ALBIN SCHANZ.

Witnesses:

OTTO WOLFF,
GASTON MÜLLER.
